UNITED STATES PATENT OFFICE.

WALTER E. WELLS AND JOHN H. MAGUIRE, OF GARDNER, MASSACHUSETTS.

AUTOMATIC TRAIN-STOP DEVICE.

1,091,810.

Specification of Letters Patent. Patented Mar. 31, 1914.

Application filed February 1, 1913. Serial No. 745,533.

To all whom it may concern:

Be it known that we, WALTER E. WELLS and JOHN H. MAGUIRE, citizens of the United States, both residing at Gardner, in the county of Worcester and State of Massachusetts, have invented a new and useful Automatic Train-Stop Device, of which the following is a specification.

The principal objects of this invention are to provide a train stop device adapted to be operated by the compressed air mechanism in common use on railway trains and some classes of street cars, and capable of being used on all the modern types of locomotives without interfering with their present accessories and attachments; also to provide an improved form of mechanism for setting the train stop device into operation, and especially to simplify the construction of this kind of mechanism.

The invention involves means whereby the setting of a signal against the train also results automatically in connecting up the compressed air system with mechanism for setting the brakes, and mechanism for operating the throttle lever to stop the engine or at least slow it down; a construction which is positively operated so that the engineer cannot prevent the operation of the mechanism; and yet which will permit him to start the train again before it has come to a full stop, thus preventing the loss of important time in cases where there is no necessity of coming to a full stop.

The invention also involves improvements in details of construction and combinations of parts as will appear hereinafter.

Reference is to be had to the accompanying drawings in which—

Figure 1 is a side view of a portion of a locomotive showing the preferred form of this invention applied thereto; Fig. 2 is an elevation of a portion of a switch showing the operating means connected therewith; Fig. 3 is a plan of a part of the throttle lever controlling mechanism shown in Fig. 1, and Fig. 4 is a sectional view on the line 4—4 of Fig. 1.

As the invention is intended to be applicable to all kinds of locomotives and other kinds of vehicles, no particular type of engine is shown, but the invention is illustrated as applied to a locomotive having the usual throttle lever 10 for controlling the engine associated with the usual curved rack

11 and detent 12. It is also shown as provided with a compressed air pipe 13 connected with the usual air brake system and adapted to set the brakes by exhausting the air from the train air line 14 by opening a valve 15. The mechanism for operating these parts in case of emergency comprises a link 20 pivoted to the movable part 21 of the signal which operates with the switch. This link being pivoted to this element is operated positively with it and it in turn swings an arm 22 which is pivoted at 23 and connected with another arm 24, the arms 22 and 24 constituting a lever. The full and dotted line positions in Fig. 2 show clearly the operation. When the signal is not set the parts are in dotted line position, and the arm 24 draws back a pin 25 on a sliding bolt 26 against an adjustable balanced spring 27. When the signal is raised or set, as shown in full lines, the arm 24 and bolt 26 are forced forward so that the bolt projects from the casing 28 until it is located in the path of an arm 30 carried by the train or engine. The balanced spring is used to make the operation easier. A casing 29 is also used to cover the operating parts of this device and protect the same from snow, ice and rain.

The arm 30 carried by the engine is pivotally mounted on a lever 31, which is provided with arms 32 and strong springs 33 connected with the arm 30. The function of the springs 33 is normally to keep the arm 30 in central position and to transmit the motion thereof yieldingly to the lever 31.

In a branch 34 of the train line air pipe and above the floor of the cab, is a valve 35 having an arm 36 thereon for operating it. The normal closed position of this valve is shown in full lines. When the train is going forward the projection of the bolt 26 into the path of the arm 30 will cause the arms 30 and lever 31 to assume the dotted line position 30^a and 31^a, in which the end of the lever engages the valve stem 36 and opens the valve. When the train meets this obstruction when backing the arms 30 and lever 31 are thrown to the opposite positions 30^b and 31^b but a spring pulls the lever 31 back as soon as the engine has passed the obstruction and causes the end of the lever to engage the valve handle 36. The motion of the lever is carried beyond the normal position to the dotted line position 31^a and this opens the valve 35.

110

The opening of the valve 35 lets air from the train line into two pipes 40 and 41. The pipe 40 is flexibly connected with a cylinder 42 having a single acting piston 43 therein normally pressed to one end of the cylinder by a spring 44. This cylinder is provided with a vent 45 and is shown more clearly in Fig. 3 as provided with a circular pedestal 46 which is mounted in a flat circular bearing 47 on a bracket 48 on the boiler or in any other convenient part of the apparatus. This permits the cylinder to turn on this pivot. This motion is limited by lugs 49 cast on the bearing. The rod 50 of the piston is provided with a shoulder 51 and with a projection 52 on the end having a slanting terminal surface. On the throttle lever is a slanting guide 53 and on the detent is an oppositely slanting guide 54. A guide 55 is located on the edge of the lever.

The admission of air into the cylinder 42 forces the piston forward in opposition to the spring and brings the projection 52 in between the guides 53 and 54. The guide 53 being fixed on the throttle lever, the cylinder 42 cannot turn on its pivot as long as the throttle lever remains stationary, but the slanting end of the rod 51 engages the slanting guide 54 on the detent and as the piston moves forward it necessarily draws the detent back from the teeth of the rack and forces the throttle lever therefrom. Then the further forward motion of the piston causes the shoulder 51 to engage the throttle lever and force it around to a position to close the throttle. As it moves around, the cylinder 42 turns on its axis to accommodate this motion as is indicated by the dotted line position. The guide 55 engages the side of the piston rod and positively forces the same to follow the motion of the throttle lever. The admission of air to the pipe 41 performs a similar function for a piston 60 in a cylinder 61, with which the pipe 41 is flexibly connected by a hose. This cylinder is pivoted on a base 62 in the same way as the cylinder 42 and the piston rod 63 engages a lever 64 between a pair of guides 65 and forces it around to open the valve 15 and admit air to the train line 14 so as to set the brakes. After these two operations have been accomplished the engineer can shut off the valve 35 by hand. The air pressure being thus released, the springs will force the plungers back to their original positions, forcing the surplus air out of the cylinders through the vent holes. The pipes 40 and 41 preferably are provided with valves 67 to govern the speed of action of the plungers.

It will be seen, therefore, that a positive acting means is provided for doing exactly what the engineer would do if he observed the signal and complied with the same. Thus the setting of the signal provides au-

tomatically for the closing of the throttle and the application of the air brakes, yet the engineer can easily reset the parts after the automatic action has been performed, and even before the train comes to a full stop if he finds that such a stop is unnecessary. The resetting of the device is done without displacing any of the apparatus and leaves it in proper condition for operating again immediately. At the same time the invention is so designed that no modification has to be made in the air brake system or throttle controlling means, and only very simple devices have to be added. It is applicable to all modern types of locomotives, and is of such a simple nature as not to get out of repair readily.

Although we have illustrated and described only one form of the invention, we are aware that many modifications can be made therein by any person skilled in the art without departing from the scope of the invention as expressed in the claims. Therefore we do not wish to be limited to all the details of construction herein shown and described, but

What we do claim is:—

1. In a train stopping device, the combination with the throttle lever and a detent therefor, said lever and detent having oppositely slanting converging guides, of an air cylinder, and a piston in the cylinder having a rod projecting from the end thereof adjacent to said throttle lever for engaging one of the guides and the throttle lever. 100

2. In a train stopping device, the combination with a throttle lever and detent therefor, of an air cylinder having a piston therein, the rod of said piston being provided with a shoulder and a projection beyond the shoulder, and oppositely slanting guides on the throttle lever and detent respectively arranged to receive the opposite sides of said projection. 105

3. In a train stopping device, the combination with a locomotive, of a lever mounted thereon, a valve having a stem in position to be engaged and operated by the lever, a spring for holding the lever in one extreme position, an arm pivoted on said lever and extending downwardly therefrom, springs on both sides of the arm for yieldingly holding it in central position, and means adapted to be projected into the path of the end of said arm for operating the arm and lever to open the valve as the locomotive moves along. 110

4. In a train stopping device, the combination with a locomotive of cylinders having means for stopping the locomotive, a valve 125 for admitting air into said cylinders, a lever movable adjacent to the valve for operating the stem thereof, and means whereby when a signal is set against the train, motion of the train forwardly past said signal will cause 130

said lever to be moved to open the valve directly, and whereby motion of the train backwardly past said signal will cause the lever first to be moved away from said valve stem and thereafter to be forced toward and against it yieldingly.

In testimony whereof we have hereunto

set our hands, in the presence of two subscribing witnesses.
